US00D566675S

(12) **United States Design Patent** (10) **Patent No.:** **US D566,675 S**
(45) **Date of Patent:** **** Apr. 15, 2008**

(54) **MOBILE PHONE**

(75) Inventor: **Young-Keun Lee**, Seoul (KR)

(73) Assignee: **Samsung Electronics Co., Ltd.**,
Suwon-Si (KR)

(**) Term: **14 Years**

(21) Appl. No.: **29/264,843**

(22) Filed: **Aug. 21, 2006**

(30) **Foreign Application Priority Data**

Jun. 9, 2006 (KR) 30-2006-0021547

(51) **LOC (8) Cl.** **14-03**

(52) **U.S. Cl.** **D14/138**

(58) **Field of Classification Search** D14/496,
D14/138, 341-347; 455/575.3, 575.1; D21/517,
D21/329, 333

See application file for complete search history.
